UNITED STATES PATENT OFFICE.

JOHN A. BODKIN, OF NEW YORK, N. Y.

RAIL-ANCHOR.

1,146,994.

Specification of Letters Patent.

Patented July 20, 1915.

Application filed July 18, 1914. Serial No. 851,789.

To all whom it may concern:

Be it known that I, JOHN A. BODKIN, a citizen of the United States, residing at the city of New York, borough of the Bronx, Bronx county, in the State of New York, have invented certain new and useful Improvements in Rail-Anchors, of which the following is a full, clear, and exact specification.

- 10 My invention relates to improvements in means for securing railroad rails against creeping during the passage of vehicles thereon, or during the periods of expansion and contraction incident to changes in temperature, and the same has for its object more particularly to provide a simple, efficient and reliable device which may be easily applied to a rail without the use of special tools or machinery.
- 15 Further, said invention has for its object to provide a rail anchor formed of a single piece of metal comprising a web having rail engaging members at its opposite ends which are adapted to be brought into wedging engagement with the inclined upper surfaces of the rail base as the anchor is adjusted from a transverse to a diagonal position, upon the rail.
- 20 Further, said invention has for its object to provide a rail anchor formed of a single piece of metal comprising a web having rail engaging means at its opposite ends, and an elevated or raised central portion adapted to engage with the underside of the rail base in order to maintain the underside of the base, adjacent to its opposite edges, free from engagement with the ends of the yoke, so as to permit of said anchor being easily adjusted from a transverse position to a diagonal position, as said rail engaging means are brought firmly into wedging engagement with the upper inclined surfaces of the rail base.
- 25 To the attainment of the aforesaid objects and ends, my invention consists in the novel details of construction, and in the combination, connection and arrangement of parts hereinafter more fully described and then pointed out in the claims.
- 30 In the accompanying drawings forming part of this specification wherein like numerals of reference indicate like parts, Figure 1 is a face view showing a strip of metal with a series of anchor blanks outlined thereon; Figure 2 is an enlarged detail side view showing an anchor blank before the

same is bent to shape; Figure 3 is a side view showing an anchor bent to shape, and engaging the base of a rail; Figure 4 is a plan or top view of a rail and tie with an anchor adjusted in position below the rail ready to be adjusted and brought into wedging engagement with the rail; Figure 5 is a similar view to Figure 4 showing the anchor adjusted to its operative position upon the rail; Figure 6 is a plan or top view showing a modified construction, and Figure 7 is an end view thereof.

In said drawings 10 designates a tie and 11 a rail supported thereon.

12 denotes an anchor formed of a single piece of sheet metal comprising a yoke 13 having rail engaging members at its opposite ends which are partially severed from the body thereon to form hooks 15, 16 which are bent in opposite directions. The upper surface of the yoke intermediate the rail engaging members 15, 16 has the portion thereof arranged midway between the ends of said rail engaging members arranged at a higher horizontal level than that of its ends, at which point the same merge with the members 15, 16. By this arrangement a central elevated member or projection 14 is formed which is adapted to engage with the underside of a rail base 17 directly below the web 18 thereof, and form a pivotal member support upon which the anchor may be partially turned.

From one end of the yoke 13 extends a post 19 which is bent slightly inwardly, and has an upper surface in line with the lower edge of the yoke 13, and its free end bent at about right angles to the post 19 to form a foot 20 whose outer side is adapted to engage with one of the vertical sides of the tie.

At Figures 6 and 7 I have shown a modified form of anchor in which the yoke 13' is provided as in the main construction with rail engaging members 15', 16', a post 19' and foot 20', and a raised central portion 14'. In the present construction however, the web 13', is in addition slightly twisted which results in off-setting the rail engaging members or hooks 15', 16' relatively to each other to the extent of about 7°.

The purpose of providing the yoke with said twist, and so off-setting the hooks 15', 16' is to render the anchor somewhat more resilient transversely and thus accentuate the wedging action with which the ends of

said rail engaging members engage with the edges of the rail.

The operation of this modified form of anchor will be obvious from the foregoing description.

- In order to attach the anchor, illustrated at Figs. 1 to 5 inclusive, to a rail it merely becomes necessary to adjust the yoke 13 transversely of the rail below the base 17 thereof, as indicated at Fig. 4. When so adjusted, the oppositely arranged rail engaging members 15, 16 will be practically parallel to each other, and with the opposite edges of the rail base 17. Hereupon the yoke 13 is brought to a diagonal position, as indicated at Fig. 5, whereby the foot 20 will be brought into close engagement with one of the vertical sides of the tie 10, and the yoke 13 brought to a position diagonally to the longitudinal direction of the rail. When the yoke has been brought to this position the rail engaging members 15, 16 will have been moved inwardly and the undersides of their free ends caused to ride upwardly upon the oppositely-inclined upper surfaces of the rail base 17, and thus firmly engage said inclined surfaces of the rail adjacent to its opposite edges thereof with a wedging action.
- The wedging action with which the rail engaging members 15, 16 engage with the inclined surfaces of the base 17 is increased owing to the fact that the yoke 13 only engages with the rail base 17 on a point directly below the web 18 of the rail, thus leaving the portions of the yoke directly below the opposite horizontal edges of the base free therefrom, and permitting of the more easy turning of the yoke to bring the undersides of the rail-engaging members 15, 16 into engagement with the inclined surfaces of the base 17. The said wedging action is further accentuated by reason of the fact that the yoke 13 is capable of yielding slightly at its outer ends as the portions thereof directly below the inner free ends of the rail engaging members 15, 16 do not contact with the underside of the base 17 or with opposite vertical edges thereof.
- Having thus described my invention, what I claim and desire to secure by Letters Patent is:—

1. A rail anchor comprising a yoke, rail-engaging means at opposite ends thereof, and a member extending upwardly from said yoke intermediate said rail engaging members, serving to cause a torsional displacement of said yoke, substantially as specified.
2. A rail anchor comprising a flat, vertically-disposed yoke, rail-engaging means at the opposite ends thereof, a member extending upwardly from said yoke intermediate said rail-engaging members, serving to cause a torsional displacement of said yoke, substantially as specified.

yoke when the same is applied to a rail, substantially as specified.

3. A rail anchor comprising a yoke, rail-engaging means at the opposite ends thereof, a member extending upwardly from said yoke intermediate said rail-engaging members, serving to cause a torsional displacement of said yoke, and means for maintaining said anchor upon a rail, substantially as specified.

4. A rail anchor formed as an integral structure comprising a flat, vertically-disposed yoke, rail-engaging means at the opposite ends thereof, and a raised central portion on said yoke arranged intermediate said rail-engaging members, and serving to cause a torsional displacement of said yoke when the same is applied to a rail, substantially as specified.

5. A rail anchor comprising a yoke, rail-engaging members at its opposite ends, and a raised central portion intermediate said rail-engaging members, serving as a pivot adapted to engage with the underside of a rail base and to cause a torsional displacement of said yoke, substantially as specified.

6. A rail anchor comprising a yoke, rail-engaging members at its opposite ends, a raised portion on said yoke extending upwardly therefrom and adapted to engage the base of a rail directly below the web portion thereof and to cause a torsional displacement of said yoke, and a tie engaging member at one of the ends of said yoke, substantially as specified.

7. A rail anchor comprising a flat, vertically-disposed yoke, rail-engaging members at the opposite ends thereof, and a member extending upwardly from said yoke midway between said rail-engaging members, substantially as specified.

8. A rail anchor formed of a single piece of sheet metal comprising a yoke, rail-engaging members at the opposite ends thereof, a member extending upwardly from said yoke intermediate said rail-engaging members, and serving as a pivotal support for said anchor and to cause a torsional displacement of said yoke, a post extending angularly inward from one end of said yoke, and a foot projecting from and disposed at an angle to said post, substantially as specified.

9. A rail anchor comprising a yoke, having its ends twisted relative to each other, rail-engaging members at the opposite upper ends thereof, a member extending upwardly from said yoke midway between said rail-engaging members, serving to cause a torsional displacement of said yoke and means for maintaining said yoke under torsional strain and duly positioned upon a rail, substantially as specified.

10. A rail anchor formed of a single piece of sheet metal comprising a yoke, rail-en-

gaging members at the opposite upper ends thereof, a member extending upwardly from said yoke midway between said rail-engaging members; said yoke being slightly twisted whereby to throw its ends and the rail-engaging members thereon out of alinement relative to each other, and means adapted to engage a tie serving to hold said anchor duly positioned upon a rail, substantially as specified.

11. A rail anchor formed of a single piece of sheet metal comprising a yoke, rail-engaging members at the opposite upper ends thereof, a member extending upwardly from said yoke midway between said rail-engaging members; said yoke being slightly twisted

ed whereby to throw its ends and the rail-engaging members thereon out of alinement relative to each other, a post extending angularly inward from one end of said yoke, 20 and a foot projecting from, and disposed at an angle to said post, substantially as specified.

Signed at the city of New York, in the county and State of New York, this 2nd 25 day of July, one thousand nine hundred and fourteen.

JOHN A. BODKIN.
